UNITED STATES PATENT OFFICE.

JOSEPH B. MURRAY, OF BROOKLYN, NEW YORK.

PORTABLE HEATING DEVICE.

1,169,560.

Specification of Letters Patent. Patented Jan. 25, 1916.

Application filed June 28, 1915. Serial No. 36,729.

To all whom it may concern:

Be it known that I, JOSEPH B. MURRAY, a citizen of the United States, residing at Brooklyn, in the county of Kings and State of New York, have invented a certain new and useful Improvement in Portable Heating Devices, of which the following is a specification.

The invention relates to portable heaters of the type which comprises a folding stand, a cup supported thereby, and a fuel-holder received in said stand below said cup.

The invention consists in the construction of the stand, and of the adjustable supporting ring for the cup, as more particularly hereinafter set forth.

In the accompanying drawings—Figure 1 is an elevation of my portable heater. Fig. 2 is a plan view of the stand with the cup removed. Fig. 3 is a detail view in section on the line 3, 3 of Fig. 1. Fig. 4 is a top view of the cup, showing the stand, supporting ring, and fuel receptacle packed therein. Fig. 5 is a bottom view of the stand, but exhibiting a modified construction. Fig. 6 is a perspective view of the supporting ring made from a single piece of wire.

Similar numbers and letters of reference indicate like parts.

30 The principal parts of my heater are the cup A, the supporting ring B therefor, the folding stand C, and the cylindrical fuel holder D. The cup A with its pivoted handle 1 and cover 2 is of well known construction. The fuel holder D is the usual can containing so-called solidified alcohol now commonly sold on the market.

The stand C is constructed in the following manner: 4 is a metal plate. 5, 6, 7 are supporting legs stamped from sheet metal and forming a tripod. As shown in Fig. 2, one of the legs, as 5, may be rigidly secured to plate 4 in any suitable way, as, for example, by a lug 9 on projection 8 which is inserted in a hole in plate 4 and has its protruding ends hammered down or upset, so that the lug forms a rivet joining the leg rigidly to the plate. The legs 6 and 7 have similar inward projections 10, 11, on each 50 of which is an ear 12, 13. The ear 12 on projection 10 is turned in the opposite direction to the ear 13 on projection 11, as shown in Fig. 2, and said ears are pivoted to the plate 4. On plate 4 are two downwardly bent stops 14, 15, so placed that when the

legs 6, 7 are in open position, as shown in Figs. 1 and 2, said legs will meet said stops. By swinging the legs 6, 7 toward the fixed leg 5, said legs may be folded together, as shown in Fig. 4. The dimensions of the legs 60 are to be such that when so folded together they may be packed in the cup A.

In order to cheapen the manufacture of the stand, I may adopt the modified form shown in Fig. 5. Here the leg 5 is provided with an ear 16, pivoted to the plate 4, and all the ears on the several legs are turned in the same direction. This makes all three legs precisely alike, interchangeable and capable of being stamped out by the same die. 65 70

In the upper end of each leg is a notch forming a shoulder 17. Each of these shoulders is received in a notch 17* formed in the lower edge of the supporting ring B. The ring B is a band of metal having at one end a slot 18, into which enters a tongue 19, formed near the opposite end of said ring, said tongue being bent over, as shown in Fig. 1. By reason of the free sliding movement 75 80 of the tongue 19 in the slot 18, the ring may be reduced in diameter so as to be packed in the cup A, as shown in Fig. 4, the resiliency of the ring then holding it closely against the cup wall. When the ring is removed from the cup and seated upon the legs, as shown in Fig. 1, it expands sufficiently to permit the cup to enter it, while the bottom of the cup rests upon the shoulders 17. The cup is, therefore, tightly held 85 90 by the ring, which also serves as a lateral support for the legs, with which it engages; so that the ring serves the double purpose as a stay for the legs and as a means of preventing displacement of the cup. 95

Instead of making the ring in the form of a metal band, as described, I may make it of spring wire, as represented in Fig. 6, the crimps 20 in said wire then taking the place of the notches and engaging in like manner with the shoulders on the legs. The ends of 100 the wire ring simply overlap.

The fuel can D is received between the vertical inner edges of the legs, as shown in Fig. 1, and rests upon the plate 4. Where all three legs are pivoted to the plate 4, the can may rest upon the pivot heads, and so be evenly supported. The size of the can is preferably to be such as to permit of its being packed in the cup together with the stand and supporting ring. 105 110

I claim:

1. A portable heating device of the type set forth, comprising a cup, a tripod having its legs pivotally connected for movement in a common horizontal plane, said legs having shoulders at their upper ends, and a spring ring having its ends slidably connected; the said ring being variable in diameter to fit within said cup or to receive said cup when 10 in engagement with said legs.
2. A portable heating device of the type set forth, comprising a cup, a stand having a support, a plurality of legs foldable one upon the other and connected to said support, and an adjustable supporting ring having notches engaging the upper extremities of said legs when in open position: the said ring being variable in diameter to fit within 15

said cup or to receive said cup when in engagement with said legs.

3. A portable heating device of the type set forth, comprising a cup, a plate, legs having lateral projections pivoted to said plate and shoulders at their upper ends, and a spring ring having its ends free and slidable upon one another, and having notches in its edge constructed to receive and rest upon said shoulders: the said ring being adapted to hold said cup.

In testimony whereof I have affixed my 30
signature in presence of two witnesses.

JOSEPH B. MURRAY.
